COTTON CLEANING APPARATUS

Wiley A. Schug, Paragould, Ark.

Application May 10, 1948, Serial No. 26,132

5 Claims. (Cl. 19—72)

1

My invention relates to improvements in cotton cleaning apparatus of the air blast, centrifugal, type.

The primary object of the invention is to provide apparatus of simple, practical construction adapted to be used on cotton picking or other machines in the field or as separate apparatus in a mill, factory or the like, the apparatus being especially designed to be supplied with picked cotton by a pressure supply pipe, and to quickly and thoroughly clean and fluff the picked cotton and discharge the same into a storage bin or the like.

Another object is to provide apparatus of the character and for the purpose above set forth, which is inexpensive to manufacture and install, will not add materially to the weight of cotton picking or other machines if used thereon, is easy to maintain clean, especially of cotton lint, and requires a minimum of servicing.

Other and subordinate objects, within the purview of my invention, together with the precise nature of my improvements, will be readily understood when the succeeding description and claims are read with reference to the drawings accompanying and forming part of this specification.

In said drawings:

Figure 1 is a view in side elevation of my improved cotton cleaning apparatus in the preferred embodiment thereof illustrating the same mounted on the storage bin shown fragmentarily;

Figure 2 is a view in plan;

Figure 3 is a view in longitudinal vertical section taken on the line 3—3 of Figure 2;

Figure 4 is a view in rear end elevation;

Figure 5 is a view in transverse section taken on the line 5—5 of Figure 1.

Referring to the drawings by numerals, my improved cotton cleaning apparatus, as shown, comprises, as its basic component, a foraminous cylinder 1 rotatably mounted, as presently described, and formed of screening 2 suitably attached to a skeleton frame comprising annular end members 3, 4, longitudinal bars 5 connecting said members, and a spider 6 at the same end of the cylinder 1 as the annular member 3 and embodying a hub 7 in the axis of said cylinder formed with a socket 8. The spider 6 is covered by the screening 2 to screen one end of the cylinder 1, hereinafter designated the rear end 9 which is screened for a reason presently clear. The opposite, front end of the cylinder 1, and which is designated 10 is open for a purpose to

2

be explained. The cylinder 1 is enclosed by a rectangular skeleton frame 11.

The frame 11 comprises rectangular front and rear ends 12, 13, longitudinal corner bars 14, a cross-bar 16 bracing the rear end 13 with upper diagonal bars 17 further bracing said end, all of the components of said frame being preferably formed of angle bars, and said frame being completely open at its front end 12.

10 For rotatably mounting the cylinder 1, grooved rollers 18 are provided at the front end 12 of said frame 11, in ninety degree angular relation, and in which the end annular member 4 of said cylinder 1 is rotatably fitted, said rollers 18 being mounted in bracket arms 19 suitably secured to the longitudinal corner bars 14 of the frame 11. Thus, the front end 10 of the cylinder 1 is rotatably supported and said cylinder is confined against endwise play. The rear end 9 of the cylinder 1 is rotatably supported by a driven shaft 20 suitably fixed at one end in the socket 8 with its other end journalled outwardly of the rear end 13 of the frame 11 in a bearing structure designated generally by the numeral 21. 15 The bearing structure 21 may take various forms but, preferably, as shown, comprises a pair of side-by-side, laterally spaced bearing forks 22 supported by a pair of legs 23 diverging downwardly to the lower corners of the frame 11 and suitably fixed thereto, said forks 22 and legs 23 being preferably formed of angle bars. Front and rear bearing plates 24, 25 and a bottom bearing plate 26, connect the bearing forks 22, the shaft 20 being journalled in the front and 20 rear bearing plates 24, 25.

The described frame 11 is supported by suitable legs 27 over the top of an open top storage bin 28 which may or may not be that of a suction cotton picking machine (not shown), and so that said frame inclines longitudinally downwardly and forwardly to similarly position the cylinder 1 for gravity discharge of cotton out of the open front end 10 of said cylinder into said bin.

40 45 The cylinder 1 is designed to be rotated from a suitable power plant, not shown, by means of a suitably connected upright shaft 29 having a universal joint connection 30 with the stub shaft 32 of a bevel gear 33, the stub shaft 32 being suitably journalled in the bottom plate 26 and the bevel gear 33 meshing with a bevel gear 34 fast on the driven shaft 20 between the front and rear bearing plates 24, 25. The power plant may be that 50 55 of a cotton picking machine if the apparatus is

used on such a machine or any other power plant if the apparatus is not so used.

A cotton supply pipe 35 for supplying picked cotton under pressure to the cylinder 1 extends into the front end 10 of said cylinder, for a short distance, at the top and in the vertical center of said cylinder, and which may be the cotton discharge pipe of a cotton picking machine, or a branch thereof or one forming part of the apparatus solely and is arranged to discharge in a line parallel with the axis of the cylinder 1.

An air pressure manifold pipe 36 extends along the bottom of the cylinder 1, outside the same, on the left-hand side of said cylinder looking from the front end of the same, and with air discharge nipples 37 spaced along the inner side thereof to discharge into the cylinder 1 at an upward angle crosswise of said cylinder.

A second air pressure manifold pipe 38 extends along the top of the cylinder 1, outside the same and on the righthand side of the cylinder, looking from the front end 4, and is provided with air discharge nipples 39 spaced along the same and arranged to discharge into the cylinder 1 at a downward angle crosswise of the cylinder.

The air pressure manifold pipes 36, 38 are arranged below and above the longitudinal center of the cylinder 1 so that the nipples 37, 39 will discharge through the lower and upper halves of the cylinder 1, respectively.

A third air pressure manifold pipe extends across the rear end 3 of the cylinder 1 adjacent the bottom thereof, as at 49, with air discharge nipples 41 on the inner side thereof arranged to discharge into said cylinder through said rear end 3. A branch pipe 42 connects said manifold pipe 49 with the adjacent end of the air pressure manifold pipe 36 in communication therewith.

An air pressure supply pipe 43 extends upwardly to the front end 12 of the frame 11 and then diagonally upwardly along the left side of said frame with a bend 44 extending across the rear end 3 of said frame 11 and suitably attached to one end of the air pressure manifold pipe 38 to support the same. A branch pipe 45 from the air pressure supply pipe 43 is suitably secured to one end of the air pressure manifold pipe 36 to support said pipe 36 which, as will be clear, supports the air pressure manifold pipe 43. The air pressure supply pipe 43 may be connected in any suitable manner with the air pressure source of supply of a cotton picking, or other machine on which the apparatus is used or with any other suitable source of air pressure supply. It may also embody a power driven air blast fan, not shown.

Referring now to the operation of the invention, the picked cotton is blown into the top of the cylinder 1, out of the cotton supply pipe 35, over the zone of discharge of air from the nipples 39 to impinge against the rear end 3 of the cylinder 1. In this connection, it is to be noted, that the nipples 39 are well below the line of discharge from said pipe 35. The cotton impinging against the rear end 3 of the cylinder 1 is thus subjected to a first stage of cleaning to remove dirt and trash therefrom which is blown out of the rear end 3 of said cylinder above the blasts of air discharged from the nipple 41. In this connection, it is explained that air issues under stronger pressure from the cotton supply pipe 35 than from the jets 37, 39, 41, whereby counteraction from the air blasts issuing from said nipples is overcome to blow dirt

and trash out of said rear end 3. The cylinder 1 is rotated, counterclockwise as indicated by the arrow in Figure 5, to revolve cotton tending to fall to the bottom of the cylinder 1 upwardly toward the discharge nipples 37 which direct jets of air through the cotton thereby subjecting same to a second stage of cleaning. The cotton is revolved by the cylinder 1 upwardly and around toward the nipples 39 where jets of air are directed therethrough, subjecting the cotton to a third stage of cleaning. The oppositely directed jets of air issuing from the nipples 37, 39 tend to revolve a mass of loose cotton in the cylinder in a direction opposite to that in which it tends to rotate under the rotation of the cylinder 1. This loosens up the fibers and the mass in the cylinder. As the cotton is cleaned it tends to gravitate out of the cylinder 1 and be discharged out of the front end 4 thereof into the bin 28. The nipples 37, 39 keep the screen 2 open for escape of dust and trash out of the sides of the cylinder. The nipples 42 serve to keep the rear end 3 of the cylinder open and facilitate discharge of the cotton out of the bottom of the cylinder.

The foregoing will, it is believed, suffice to impart a clear understanding of my invention, without further explanation.

Manifestly, the invention, as described, is susceptible of modification, without departing from the inventive concept, and right is herein reserved to such modifications as fall within the scope of the appended claims.

Having described the invention what is claimed as new is:

1. Apparatus for cleaning cotton comprising a cylinder of mesh material for receiving cotton to be cleansed and having a screened rear end and an open front end, means to mount said cylinder for rotation about its axis in a horizontally inclined position with its open end lowermost for gravity discharge of cleaned cotton out of said end, an air pressure pipe opening into the front end of the cylinder at the top and in the vertical center of said end for blowing cotton to be cleansed into the top of the cylinder against said rear end to separate dirt and trash from the cotton and blow the same out of said rear end whereby the cotton is subjected to a first stage of cleaning, means to rotate said cylinder whereby revolving motion in the same direction is imparted to cotton in the cylinder, and means for directing jets of air through said cylinder crosswise thereof from opposite sides of the same to further separate dust and dirt from the cotton.

2. Apparatus for cleaning cotton comprising a cylinder of mesh material for receiving cotton to be cleansed and having a screened rear end and an open front end, means to mount said cylinder for rotation about its axis in a horizontally inclined position with its open end lowermost for gravity discharge of cleaned cotton out of said end, an air pressure pipe opening into the front end of the cylinder at the top and in the vertical center of said end for blowing cotton to be cleansed into the top of the cylinder against said rear end to separate dirt and trash from the cotton and blow the same out of said rear end whereby the cotton is subjected to a first stage of cleaning, means to rotate said cylinder whereby revolving motion in the same direction is imparted to cotton in the cylinder, means for directing jets of air through said cylinder crosswise thereof from opposite sides of the same to further separate dust and dirt from

the cotton, and means to direct jets of air through said rear end at the bottom of the cylinder to prevent clogging of said rear end.

3. Apparatus for cleaning cotton comprising a cylinder of mesh material for receiving cotton to be cleansed and having a screened rear end and an open front end, means to mount said cylinder for rotation about its axis in a horizontally inclined position with its open end lowermost for gravity discharge of cleaned cotton out of said end, an air pressure pipe opening into the front end of the cylinder at the top and in the vertical center of said end for blowing cotton to be cleansed into the top of the cylinder against said rear end to separate dirt and trash from the cotton and blow the same out of said rear end whereby the cotton is subjected to a first stage of cleaning, means to rotate said cylinder whereby revolving motion in the same direction is imparted to cotton in the cylinder, and means for directing jets of air through said cylinder crosswise thereof from opposite sides of the same to further separate dust and dirt from the cotton, the last mentioned means comprising air pressure manifold pipes extending alongside opposite sides of the cylinder with air jet nipples spaced along the same.

4. Apparatus for cleaning cotton comprising a cylinder of mesh material for receiving cotton to be cleansed and having a screened rear end and an open front end, means to mount said cylinder for rotation about its axis in a horizontally inclined position with its open end lowermost for gravity discharge of cleaned cotton out of said end, an air pressure pipe opening into the front end of the cylinder at the top and in the vertical center of said end for blowing cotton to be cleansed into the top of the cylinder against said rear end to separate dirt and trash from the cotton and blow the same out of said rear end whereby the cotton is subjected to a first stage of cleaning, means to rotate said cylinder whereby revolving motion in the same direction is imparted to cotton in the cylinder, means for directing jets

of air through said cylinder crosswise thereof from opposite sides of the same to further separate dust and dirt from the cotton, the last mentioned means comprising air pressure manifold pipes extending alongside opposite sides of the cylinder with air jet nipples spaced along the same, and an air pressure pipe for supplying said manifold pipes and supporting the same.

5. Apparatus for cleaning cotton comprising a cylinder of mesh material for receiving cotton to be cleansed and having a screened rear end and an open front end, means to mount said cylinder for rotation about its axis in a horizontally inclined position with its open end lowermost for gravity discharge of cleaned cotton out of said end, an air pressure pipe opening into the front end of the cylinder at the top and in the vertical center of said end for blowing cotton to be cleansed into the top of the cylinder against said rear end to separate dirt and trash from the cotton and blow the same out of said rear end whereby the cotton is subjected to a first stage of cleaning, means to rotate said cylinder whereby revolving motion in the same direction is imparted to cotton in the cylinder, and means for directing jets of air through said cylinder crosswise thereof from opposite sides of the same to further separate dust and dirt from the cotton, the last mentioned means comprising air pressure manifold pipes extending alongside opposite sides of the cylinder with air jet nipples spaced along the same.
